[57] **CLAIM**

The ornamental design for a tool carrier, as shown and described.

DESCRIPTION

FIG. 1 is a perspective view of the front of the tool carrier;

FIG. 2 is a frontal view of the tool carrier;

FIG. 3 is a rear view of the tool carrier; and,

FIG. 4 is a perspective view of a rear view of the tool carrier.

The broken line showing of a bucket and handle is for illustrative purposes and forms no part of the claimed invention.

The cross-line pattern which is partially shown for ease of illustration, represents a conventional fabric and is understood to repeat uniformly throughout the indicated areas.
